APPARATUS FOR ANALYZING DATA
ON CARDS

Allan A. Twichell, Bethany, Conn.

Application September 30, 1944, Serial No. 556,602

2 Claims. (Cl. 33—76)

1

This invention relates to apparatus for analyzing in percentages classified data on a group of cards.

In the analysis of statistical materials, whether in business, government, or science, the ends most commonly sought are two. One is to reveal the significant internal relationships of a single series of cases. The other is to facilitate meaningful comparisons between two or more series. Percentage is the common denominator of statistics, and percentage determination is the medium used universally to reveal the meaning and give comparability to bodies of statistical data.

Two kinds of cards are commercially produced and most widely used in statistical processing: the "Hollerith" type of machine-sorted card with internal columnar punching and the "Keysort" type of card which is a marginally punched card and usually sorted manually by means of selector rods.

Under present methods, percentage determination with either the machine or the marginal punch-card involves three steps: (1) sorting the cards into classes, (2) counting the cards in each class, (3) calculating the desired percentage characteristics from the numbers of cards in each of the various classes. Machine cards are sorted rapidly (though one by one) and are counted as they are sorted. Marginally punched cards are sorted in groups by a semi-instantaneous process, but under methods thus far available they are counted after the sorting. Although the sorting operation with marginally punched cards is very rapid, the need for counting of the sorted cards has been a serious drawback to the use of these cards in statistical analysis because of the time consumed. The final step of percentage calculation from the counts is essentially the same with both types of cards.

It is the principal object of my present invention to provide a simple apparatus for efficiently and expeditiously analyzing in percentages selected classifications of data contained on cards in a group of an unknown number.

A further object of the invention is to provide an improved apparatus for the analysis of data indicated upon the margins of sheetlike record forms, which apparatus enable the analysis to be made by measuring, percentagewise, the thickness of a group of such forms disposed flatwise against each other.

Still another object of the invention is to provide a rack or tray for containing a group of record forms or cards supported upon their edges, and supporting a scale adjacent one edge of the group of cards in such a manner that the scale

2

may be moved in a direction parallel to the face of the cards, and also may be moved in a direction transversely across the edges of the group of cards, and in addition may be swung pivotally with respect to its support whereby any point upon the scale may be brought into registration with a predetermined point upon the group of cards or other record members.

My invention is exemplified in the following 10 description and an apparatus for use in practicing the method is illustrated by way of example in the accompanying drawings in which:

Fig. 1 is a plan view of an apparatus for practicing my improved method.

15 Fig. 2 is a longitudinal sectional view therethrough taken on line 2—2 of Fig. 1.

Fig. 3 is a perspective view of a stack of cards of the type to be analyzed by my method.

20 Figs. 4, 5, and 6 are diagrammatic views illustrating certain uses of my method.

Referring more particularly to the accompanying drawings, I have there shown a simplified form of apparatus for practicing my method.

In general the device consists of a card supporting tray 10 having an upstanding front wall section 11, a back or rear wall 12 and an intermediate positioned follower block 14. The top of the front wall section is formed with a longitudinal dove-tail groove 16. A slide member 17 is provided having a dove-tail member 18 engaging the groove 16 so that the slide 17 may be reciprocated longitudinally of the tray. Pivotally connected adjacent one end of the slide 17 is a calibrated scale 19. The pivotal attachment of the scale 19 to the slide 17 is accomplished by means of a pivot bolt 20 which projects through a slot 21 extending longitudinally in the scale and thence through the slide 17. At its top the bolt 20 is fitted with a wing nut 22 so that the scale 19 may be clamped in fixed relation to the slide 17 or may be released so that its position may be adjusted longitudinally and rotatably relative to the slide 17.

As will be seen from the drawings, the mounting of the scale 19 on the slide 17 is such that the bottom of the scale 19 is at approximately the top of the front wall section 11 of the tray 10 and the top of the follower block 14. The width or height of the cards 23 to be used in the tray 10 is such that when they are clamped between the follower block 14 and the front wall section 11 of the tray 10 they will be arranged obliquely to the bottom of the tray 10 with their top edges disposed substantially on the level on the top of the front wall section 11 and the follower block 14 so

that the scale 19 may pass thereover in contact therewith. The cards may, of course, be disposed perpendicularly to the bottom of the tray 10, if so desired.

The scale 19 is formed with a central longitudinal opening 24 the opposite side edges of which are calibrated from zero to 100. In this instance the calibrations indicate percentage. It will be noticed that the calibrations are numbered in reverse order so that the percentages can be read from either side of the stack of cards over which it passes.

The operation is as follows: When it is desired to analyze the data upon a group of cards 23 or other record forms, this group is placed in the tray 10 in an upright or perpendicular position and will drop by gravity against the front wall 11 so that their margins will be aligned.

The follower 14 is now brought forwardly to compress the cards against the inclined surface of the wall 11, thus bringing them into an inclined position in which their upper edges will be substantially flush with the upper edges of the wall 11 and follower 14. The surfaces of the front wall 11 and follower block 14 may be perpendicular to the bottom of the tray 10 if so desired. The scale 19 is now adjusted until the zero and 100 percent calibrations thereon register with the face of the first and back of the last cards, respectively, of the stack. As shown in Figs. 1 and 3, the cards 23 nearest the observer are slotted as at 25, while those at the back of the group are not so provided. This would be the case with a simple "yes-no" type of data. When the scale 19 has been properly positioned, as described above, the slide 17 is moved within the dove-tailed groove 16 until the edge of the scale 19 registers with the slotted notch upon the last card so punched. The operator will at once be able to read the percentage of the notched cards relatively to the whole group, and also the percentage of those which have not been so notched.

It will be understood from the further description herein that if the cards are so punched and slotted as to be sortable in a number of classifications, any number of readings may be made from the scale 19 by simply moving this scale 19 longitudinally of the edges of the cards, that is, by moving the slide 17 along the groove 16, so that the edge of the scale 19 will be brought into proximity with the notches at various places along the edges of the cards 23.

For the purpose of illustration, in Fig. 4 I have selected the simplest application of my method and device. One of the simplest examples of the use of marginally slotted cards is the instance where a single hole or notch is assigned to represent a "yes-no" item or any characteristic with only two possible classifications. For instance, where each card represents a dwelling unit, a certain hole in the card is used to designate the race of the head of the household. For a non-white head of the household that hole is slotted out to the edge of the card while the card is left unslotted for a white head of the household. When a stack of these cards has been sorted for a single classification of this type, the cards reassembled in the normal fashion, all of the cards which have been slotted for that item or classification will lie together at one side of the stack. When viewed from the top edge, such slotted cards exhibit a continuous gap, as illustrated in Fig. 3.

To illustrate the method of finding the per-

centage distribution of data in a "yes-no" or other two-part classification such as the example given above, I have diagrammed such an example in Fig. 4. This figure illustrates the 100-part scale 19 applied to a stack of cards where 47 of 100 cards were slotted for one classification. With the cards in uniform compression the front end of the gap in these cards falls at point 47 on the scale as shown.

10 In this simple instance there is thus measured 47 percent incidence of nonwhite household heads, without counting the sorted cards and without calculation. The obverse value, 53 percent white household heads, is obtained by simple subtraction from 100 percent.

15 It is, of course, not necessary that the total number of cards be a round figure as used for illustration here. Had the total number of cards in this instance been 97, 182, or any other number within the capacity of the scale, the percentage ratio of 47 cards to the total would be obtained with equal ease by instantaneous direct reading of the scale.

20 To illustrate the application of the method to 25 determine the percentage distribution of data in a many-part classification, reference is had to Fig. 5 which represents a group of cards slotted for an item with seven classes. In this instance class 1 is at the front of the stack and class 7 at the back. It is therefore desirable to use the reverse percentage scale on the opposite side of the scale 19, reading from zero at the front end and 100 at the back end. Taking this item to be the number of rooms in the dwelling 30 unit, the percentage distribution is read directly from the scale, as follows:

40	7% of the units have 1 room; scale readings -----	0 to 7
40	10% of the units have 2 rooms; scale readings -----	7 to 17
45	18% of the units have 3 rooms; scale readings -----	17 to 35
45	21% of the units have 4 rooms; scale readings -----	35 to 56
50	22% of the units have 5 rooms; scale readings -----	56 to 78
50	13% of the units have 6 rooms; scale readings -----	78 to 91
50	9% of the units have 7 rooms; scale readings -----	91 to 100
	100% check-total.	

55 By my method, I have replaced both the laborious counting of sorted cards and the calculation of percentages from these counts by a single series of instantaneous scale readings. Since the work eliminated is a dual series of complex operations, the time-savings can be very great. I have determined from actual practice that at least 80% of the time required to count and calculate is saved.

60 Among the most revealing statistical devices are the median or mid-point in an ordered series 65 of cases, and the quartiles or quarter-points. Determination of these values facilitates comparison of several series, and provides a standard condensed expression of the composition of a single series. Octiles or deciles, the values of 70 the eighth-points or tenth-points in a series, are sometimes useful.

With ordinary punched card methods, whether machine or manual, median and quartile determinations are made by a complicated series of 75 steps, as follows: Percentage distribution is de-

terminated by count and calculation as described above. The percentages falling in the various classes are then cumulated. The fourth and final step is to determine which class must contain the first quartile, which class the median, and which the third quartile. With my present method, however, these four steps are replaced by instantaneous scale readings. The values of the first quartile, median, and third quartile are read, respectively, from the classes which fall beneath points 25, 50, and 75 on the scale when it is moved laterally so as to intersect the slots for the item in question. The median for any series is the value "at a point so chosen that half of the cases in the series are on one side of it, and half on the other." Only if the series has an odd number of cases will the median, quartiles, octiles, etc., coincide with the values of actual cases in the series. In an ordered series of 100 cases, for example, the median is the value midway between the values of the 50th and 51st cases. But with 101 cases the median is the 51st case, the quartiles are the 26th and 76th cases.

This peculiarity of median and quartiles has a favorable bearing on the accuracy of my method in median and quartile determinations. The diagonal scale carries 100 units of length but 101 point markings (0 to 100). Points 25, 50, and 75 thus actually become the 26th, 51st and 76th cases of a 101 case series. Therefore, these points give the precise location of median and quartiles in an ordered series of cards. A similar relation holds for octiles, deciles, etc.

For example, referring again to Fig. 5, it is seen that by this method that the median dwelling unit contains four rooms, the unit at the first quartile three rooms, and the unit at the third quartile five rooms. The practical significance of this is, of course, that this body of data is quickly characterized by showing that at least 50 percent of the units lie within the narrow size range of three, four, or five rooms.

In this instance class 1 equals one room, class 2 equals two rooms, and so on. There is no range within the classes, and the class values as read from the scale are also the absolute values of median and quartiles.

In many situations the classes will contain a range of values such as monthly rent per dwelling unit, where class 1 might represent rents from \$0 through \$9.99, class 2 from \$10.00 through \$19.99, and so on by ten dollar intervals to \$60.00 and over for class 7. Assuming now that Fig. 5 represents this situation, we find by direct scale readings that the median lies between \$30.00 and \$40.00 (class 4), with the quartiles between \$20.00 and \$30.00 (class 3), and \$40.00 and \$50.00 (class 5), respectively.

Under previous methods of analysis, the amount of calculation involved in this kind of determination is considerable. This amount of labor has probably discouraged median and quartile determinations in many situations where they would be useful, and it has generally discouraged more refined determinations, such as octile or decile values, which can shed valuable further light in certain situations.

It will be seen that since this invention eliminates all counting and calculation for the types of analysis thus far discussed, it is quite as easy and virtually as quick to determine octile or decile values as medians and quartiles alone.

I have found in actual practice that my invention has made it economically possible to adopt as standard analytic practice a considerably

more refined division of statistical data than would be practicable with any available other method. To see what this means in practice, consider the situation, simplified from an actual instance, presented by the two following tables. These tables plot for purposes of comparison, the classes of penalty scores incurred by dwelling units in four survey areas. These scores are a reliable measure of housing quality, and it is intended to judge from them whether one area is generally better or worse than another. Since these are penalty ratings, a score in a high class denotes a poor condition. In lieu of bar-graph presentation, ordinarily used with this type of material, the figures are staggered in the columns to give them semi-graphic positions.

The values are as follows:

		Class of Dwelling Unit Score At—				
		Best Score	First Quartile	Median	Third Quartile	Poorest Score
20						
25	Area 1.....	4	6	7	8	14
	Area 2.....	2	7	8	9	13
	Area 3.....	1	8	9	10	12
	Area 4.....	3	9	10	11	13

A regular progression from better to worse appears from area 1 to area 4 in terms of the median and quartile values. For the middle 50 percent of cases in these areas there is a consistent quality relationship. This is completely lost, however, at the extremes of the ranges. At both extremes area 1 shows quality poorer by one class than area 4, and the end pattern is generally confused.

By cutting off 5 percent of the cases at either end the pattern is cleared as these values appear:

		Class of Dwelling Unit Score At—				
		5% from Best	First Quartile	Median	Third Quartile	5% from Poorest
40						
45	Area 1.....	5	6	7	8	9
	Area 2.....	6	7	8	9	10
	Area 3.....	7	8	9	10	11
	Area 4.....	8	9	10	11	12

This table shows that not only for 50 percent but for 90 percent of the cases there is a regular progression from better to worse in areas 1 to 4. Conversely there is located a fortuitous scatter within the 5 percent of cases at each extreme.

To disclose this relationship with ordinary methods would call for additional calculation at best. With my method and apparatus it requires only two additional scale readings for each area, namely, the classes which fall beneath point 5 and point 95 on the scale. Hence, these finer determinations can readily be adopted as standard practice, and it is quite as easy to strip off 2 percent, 7 percent or 10 percent of the cases at each extreme as the 5 percent chosen here.

My method can also be employed to find absolute values of median and quartiles in a series where each class contains a range of values.

When each of the classes of an item covers a range of values, as in the case of monthly rent discussed above, it may be sufficient to determine the classes which contain the median and quartile values. The procedure for this has been given. But assume that for internal analysis of a series or for comparisons between series the absolute values of median and quartiles is needed.

Fig. 6 shows cards slotted for such a series.

The item illustrated here is: Number of square feet of bedroom area per occupant of the dwelling unit. In a housing survey such an item would constitute a basic measure of overcrowding. Class 1 is slotted for a dwelling unit with less than 40 square feet of bedroom area per occupant, class 2 for 40 to 44.9 feet, and so on by 5 foot intervals through class 7 with 65 square feet or over.

In this example, statistically correct values of 40.75 square feet for the first quartile and 48.6 square feet for median are quickly found by scale readings from the sorted cards plus a rapid calculation as follows:

First quartile

- (a) 1st quartile (point 25 on scale) falls in class 2.
- (b) Range of class 2 is 5 square feet (40.0 through 44.9).
- (c) Class 2 subtends 20 units on the scale (point 22 to point 42).
- (d) Each scale unit in class 2 represents a range of .25 square feet.

$$\left(\frac{5}{20} \text{ (square feet)} \right) = \frac{5}{20} = .25$$

- (e) 1st quartile is 3 scale units above the bottom of class 2 on the scale (point 25 minus point 22=3).
- (f) 1st quartile value is 40.0 square feet plus $(3 \times .25 \text{ square feet})$ or 40.75 square feet of bedroom space per occupant.

Median

- (a) Median (point 50 on scale) falls in class 3.
- (b) Range of class 3 is 5 square feet (45.0 through 49.9).
- (c) Class 3 subtends 11 units on the scale (point 42 to point 53).
- (d) Each scale unit in class 3 represents a range of .45 square feet

$$\left(\frac{5}{11} = .45 \right)$$

- (e) Median is 8 scale units above the bottom of class 3 on the scale (point 50 minus point 42=8).
- (f) Median value is 45.0 square feet plus $8 \times .45 \text{ square feet}$ or 48.6 square feet of bedroom space per occupant.

By the same method the third quartile value is shown to be 59.0 square feet.

My method has the further advantage that the accuracy of results is not affected if the thickness of card stock is changed from one group of cards to another. Similarly, accuracy is not affected if, say, the unit thickness of cards is increased by absorption of atmospheric moisture.

One of the reasons for this accuracy is the fact that the cards are stacked obliquely so that a portion of the face of each card is exposed. While

This is not precisely illustrated in the drawings because of the minuteness of the dimensions involved, however, it will suffice to say that when a stack of cards is arranged obliquely with its bottom and top edges in parallelism a portion of the face of each card is exposed.

The four types of analysis which have been illustrated and described comprise, with their normal variations and combinations, a large part of the usual statistical operations with mass data.

If the number of cards in the various groups to be analyzed varies considerably, it is contemplated that scales 19 of different lengths may be employed. A scale four and a half inches long, for example, may be employed with as many as 400 cards or as few as 30 cards, depending upon its angular setting.

While I have shown and described my invention specifically, it will be understood that it is not to be limited to specific examples set forth, but is capable of modification and variation within the spirit of the invention and within the scope of the claims.

Having thus described my invention, what I claim and desire to secure by Letters Patent is:

1. In a device for analysis of data upon cards or similar record forms, means providing relatively adjustable substantially parallel walls for supporting a group of cards with an edge of each lying in substantially the same plane, an indicia bearing percentage scale pivotally mounted on one of said walls and adjustable for registration of two of its indicia with remote cards of said group along a line extending transversely over the edges of all cards in said group.
2. In a device for analysis of data upon cards or similar record forms, means providing relatively adjustable substantially parallel walls for supporting a group of cards with their upper edges lying in substantially the same plane, an indicia bearing percentage scale slidably mounted with respect to one of said walls for movement parallel to said edges, and pivotally mounted for registration of spaced indicia thereof with remote cards of said group along a line extending transversely over said edges of all cards in said group.

ALLAN A. TWICHELL.
